POLE TOP ELECTRICAL TRANSFORMER

Bertrand V. Giegerich, Pittsfield, Mass., assignor to
General Electric Company, a corporation of New York

Filed Jan. 10, 1964, Ser. No. 78,155

Term of patent 14 years

(Cl. D26—15)

FIGURE 1 is a top view of a pole top electrical transformer showing my new design;

FIGURE 2 is a side view of the transformer; and

FIGURE 3 is a side elevation view showing a modified form thereof, wherein the vertical diameter is increased slightly by the addition of a short, substantially cylindrical portion.

The broken line showing of a portion of a pole in FIGS. 2 and 3 is for illustrative purposes only.

I claim:

The ornamental design for pole top electrical transformer, as shown and described.
